UNITED STATES PATENT OFFICE.

FREDERICK C. LYNDE, OF MANCHESTER, COUNTY OF LANCASTER, ENGLAND.

PORTABLE TABLE OR DESK.

SPECIFICATION forming part of Letters Patent No. 425,814, dated April 15, 1890.

Application filed October 23, 1889. Serial No. 327,888. (No model.)

To all whom it may concern:

Be it known that I, FREDERICK CHARLES LYNDE, a subject of the Queen of Great Britain and Ireland, residing at Manchester, in the county of Lancaster, England, have invented an Improved Portable Table or Desk, of which the following is a specification.

My invention consists, principally, in so constructing a portable table or desk that it may be either directly or indirectly attached, connected, or applied to the arm or wrist (or both) of the person wishing to use such table or desk in such a way that the vibration or motion experienced when traveling in a railway or other carriage or in a steamboat or other conveyance may be communicated equally, or nearly so, to the arm and hand of the person and to the table or desk itself, so that the two always move simultaneously and in the same direction, thus enabling the user to write more legibly and easily and to avoid the irregularities which would otherwise be inevitable. Such being the nature and object of my said invention, I will now proceed to explain the manner in which the same is to be performed or carried into practical effect; and in order that the same may be clearly understood I have annexed hereunto two sheets of drawings illustrative thereof, and have marked the same with figures and letters of reference corresponding with those in the following explanation thereof.

Figure 1 on the drawings illustrates a simple form of my improved portable table or desk, and Figs. 2 and 3 show slight modifications thereof. Figs. 4, 5, 6, and 7 illustrate methods of supporting or suspending the table or desk, which may be adopted when preferred, in order to diminish or remove the weight of the table or desk from the wrist or arm and to assist in supporting the same.

The form of the table or desk *a* may be varied to suit circumstances; but I prefer to make it somewhat in the form of a spade with a short handle, as shown on the drawings.

The handle *b* of the table or desk is to be attached or connected to the arm or wrist (or both) of the user by means of straps *c*, Fig. 1, or by india-rubber band or bands *d*, Fig. 2, or other suitable device, or it may be simply passed up the sleeve of the user, which (if the sleeve is not too loose) will afford a sufficient

connection (without straps or bands) between the arms of the user and the table or desk. The handle *b* may also be fastened to the arm 55 by a cord *c*, provided with a series of knots *x*, (see Fig. 5,) one of which is caught beneath the slit or notch *b*, cut in the handle *b*, and thus the cord will form loops of various sizes.

In some cases I propose to have a rest *e* pivoted to the handle *b*, as shown at Fig. 3, or in place thereof a rest for the hand or wrist may be arranged so as to slide to and fro in a transverse slot in the part *a*. The blade *a* in all cases projects underneath the hand and 65 forms a small table or desk for writing or drawing upon.

If an additional support is required, so as to take the weight of the table or desk off the wrist or arm, the desk may be provided with 70 a prop *f*, fixed underneath, as shown at Fig. 4, so as to rest against the ground or upon the seat or any other suitable projection; or, instead of a prop beneath, the desk may be hung from any convenient fixed part of the carriage 75 or conveyance above the user, (such, for example, as the parcel-rack of a railway-carriage,) either by a single sling *k* (elastic or otherwise) and hook *k*, or its equivalent, as shown at Fig. 5, or by a double sling *k*, *k*, and 80 hook *k*, or its equivalent, (see Fig. 6,) in which latter case the arm may pass between the two cords of the rearmost sling *k*, so as to assist in steadyng the desk; or it may be suspended from the neck or shoulders by a cord, band, 85 or sling similar to that shown at Fig. 5.

The desk or slab *a* may be made adjustable to any angle required and may be provided with a slit in it, as shown at *g*, through which the paper *h* is allowed to pass, as shown at Fig. 90 2, or a roll of paper *i* may be attached to the under side of the slab *a* (see Fig. 5) or in any other convenient position, so that the writer may unroll the paper, which may be perforated across at suitable distances, as required. 95

The slab may be provided with a sheet or pad *m* of writing or blotting paper and with holding-down clips or springs *n*, Fig. 6, or an india-rubber band *n* (see Fig. 4) or other suitable appliances for keeping the paper 100 steady. It is evident, also, that an inkstand *o* (see Fig. 3) may, if desired, be fixed upon the apparatus, and various other requisites—such as pen-brush, pen-holder, and pencil-clips—

may also be added. (See, also, Fig. 3.) The slab may also, when supported by a sling or prop, be made sufficiently wide to serve as a rest for both arms of the user, in which case it need not be strapped or connected to the arm or wrist. (See Fig. 7.) A similar table may also be employed by artists and others for sketching and other useful purposes.

I claim as my invention—

- 10 1. A traveler's portable writing-table consisting of a slab adapted to be connected to the arm or wrist of the user, whereby the vibration or motion of a carriage or conveyance may be communicated equally, or nearly so, both to the arms and hand of the user and also to the table itself, substantially as described.
- 15 2. A traveler's portable writing-table consisting of a slab with a handle part adapted to be passed up the sleeve of the user, so as to connect it to his arm, the outer end of the slab being of suitable size and shape to support the hand of the user and the paper to be written on, substantially as described.

3. A portable writing-table consisting of a slab provided with fastenings to attach it to the arm or wrist of the user, substantially as described.

4. A portable writing-table consisting of a slab adapted to be connected to the arm or wrist of the user and having a supporting-prop beneath, substantially as described.

5. A portable writing-table consisting of a slab adapted to be connected to the arm or wrist of the user and having a suspending sling or slings, substantially as set forth.

6. A traveler's portable writing-table consisting of a slab provided with a suspending device adapted to suspend the slab from any convenient fixture in a carriage or conveyance, substantially as set forth.

In testimony whereof I have signed my name to this specification in the presence of two subscribing witnesses.

FRED. C. LYNDE.
